US0D1092527S

(12) **United States Design Patent** (10) **Patent No.:** **US D1,092,527 S**
(45) **Date of Patent:** **** Sep. 9, 2025**

(54) **DISPLAY SCREEN OR PORTION THEREOF WITH GRAPHICAL USER INTERFACE**

(71) Applicant: **Alibaba Singapore Holding Private Limited**, Singapore (SG)

(72) Inventors: **Ruiyao Jiang**, Hangzhou (CN); **YuJen Huang**, Hangzhou (CN); **Chao Guo**, Hangzhou (CN); **Xiaohua Chen**, Hangzhou (CN); **Xuguang Qi**, Hangzhou (CN); **Ang Gao**, Hangzhou (CN); **Siqi Cheng**, Hangzhou (CN)

(73) Assignee: **ALIBABA SINGAPORE HOLDING PRIVATE LIMITED**, Singapore (SG)

(**) Term: **15 Years**

(21) Appl. No.: **35/521,792**

(22) Filed: **May 25, 2024**

(80) **Hague Agreement Data**

Int. Filing Date: **May 25, 2024**

Int. Reg. No.: **DM/238557**

Int. Reg. Date: **May 25, 2024**

Int. Reg. Pub. Date: **Jul. 26, 2024**

(30) **Foreign Application Priority Data**

Nov. 30, 2023 (CN) 202330789623.1

(51) **LOC (15) Cl.** **14-04**

(52) **U.S. Cl.**

USPC **D14/485**

CLAIM

The ornamental design for a display screen or portion thereof with graphical user interface, as shown and described.

DESCRIPTION

FIG. 1 is a front view of a display screen or portion thereof with graphical user interface showing the claimed design; FIG. 2 is a front view of a second embodiment thereof; and, FIG. 3 is a front view of a third embodiment thereof. The dashed broken lines in the figures show a display screen or portion thereof, and form no part of the claimed design. The area between the dashed broken lines and dot dash lines show portions of the graphical user interface that form no part of the claimed design.

1 Claim, 3 Drawing Sheets
